UNITED STATES PATENT OFFICE.

GUY H. SILVA, OF SAN DIEGO, CALIFORNIA.

IGNITION SYSTEM FOR INTERNAL-COMBUSTION ENGINES.

1,280,077.

Specification of Letters Patent. Patented June 12, 1917.

Application filed March 16, 1916. Serial No. 84,713.

To all whom it may concern:

Be it known that I, GUY H. SILVA, a citizen of the United States, residing at San Diego, in the county of San Diego and State of California, have invented certain new and useful Improvements in Ignition Systems for Internal-Combustion Engines, of which the following is a specification.

My invention relates to an ignition system for internal combustion engines and the objects of my invention are: first, to provide an ignition system which automatically advances the spark with the increase of the speed of the engine and is retarded with the decrease of the speed thereof, thus synchronizing the timer with the engine; second, to provide a system of this class which is positive in its action; third, to provide a system of this class which is simple and economical of construction, durable, easily installed and does not readily get out of order; fourth, to provide an ignition system of this class which utilizes a minimum of space in proportion to its efficiency.

With these and other objects in view as will appear hereinafter, my invention consists of certain novel features of construction, combination and arrangement of parts as will be hereinafter described in detail and particularly set forth in the appended claims, reference being had to the accompanying drawings and to the characters of reference thereon which form a part of this specification, in which:

Figure 1 is a side elevational view of my specially constructed magneto generator in connection with a diagrammatic view of the remainder of the system and showing the mechanism in position for charging the condensers. Fig. 2 is a similar view showing the timer in contact with the condensers being fully charged and discharging into the primary coil of the transformer, and Fig. 3 is a diagrammatic view in a modified form of the construction and arrangement aside from the magneto generator, showing the timer in the same relative position shown in Fig. 1.

Similar characters of reference refer to similar parts throughout the several views.

The magnet 18, two-pole armature 1, commutator 2, commutator segments 3 and 4, brushes 5 and 6, terminals 7 and 8, condensers 9, timer 10, timer contact 11, timer switch 12, terminal 13, terminal 14, terminal 15, terminal 16, transformer bar 17,

transformer primary winding 19, transformer secondary winding 20, conductor 21, conductor 22, conductor 23, conductor 24, conductor 25, ground 26 and distributing conductors 27 constitute the principal parts of my ignition system.

The magnet 18 is provided with two permanent magnetic fields 18^a and in this magnet is mounted the two-pole oppositely disposed armature 1 and engaging with said poles in the commutator 2 mounted on the axle 2^a which commutator is provided with the two oppositely disposed segments 3 and 4 and engaging with said commutator are the oppositely disposed brushes 5 and 6 so positioned as to collect current generated by the armature at the highest peak of wave. Connected in parallel to these brushes 5 and 6 are the condensers 9 by means of the terminals 7 and 8 and conductors 22, 23 and 24. Connected to conductor 24 is a timer 10 which in the preferred construction as shown in Figs. 1 and 2 is provided with a contact 11 as shown in Figs. 1 and 2 of the drawing. Revolvably mounted in the timer 10 is a double contact timer switch 12 which is so connected to the axle 2^a of the commutator 2 in any way desired that it revolves at the same rate of speed as said commutator so as to be in perfect synchronism therewith. Electrically connecting the condenser 9 with the revolving switch 12 is a primary transformer coil 19 by means of the terminals 13 and 14 and conductors 22 and 25. This transformer is also composed of the bar 17 and secondary winding 19 forming a spark coil. The secondary winding is grounded through terminal 15 and ground 26. Connected to the other end of said secondary winding is the terminal 16 and conductor 21 to distributor 27 which is the wiring for the cylinders of an internal combustion engine in their order.

It will be noted that after the segments 3 and 4 of the commutator have passed the point of contact with the brushes 5 and 6 as shown in Fig. 2 of the drawings the condensers 9 are left in a highly charged state, that by bringing the switch 12 in engagement with the contact 11 will cause the condenser 9 to discharge into the primary winding 19 of the transformer thus causing two sparks with each revolution of the commutator 2 and timer switch 12, which are distributed in their order to the cylinders by the distributor 27.

In the modified form of construction shown in Fig. 3 of the drawings, the construction is the same as in Figs. 1 and 2 throughout except that there is provided a 5 double set of condensers 9 and 9^a connected in series and the timer 10 is provided with two contacts 11 and 11^a ninety degrees apart. The operation in the modified form is as follows: After the segments 3 and 4 of the 10 commutator have passed the point of contact with the brushes 5 and 6, both sets of condensers are left in a charged state, then when the timer switch 12 engages with contact 11, the condenser 9^a discharges into the primary winding 19 of the transformer and 15 ninety degrees later the switch 12 engages with the contact 11^a causing the condenser 9 to discharge into the primary winding 19 of the transformer. Thus it will be noted 20 that twice the number of sparks will occur with each revolution of the commutator so that there will be four sparks with each revolution in this modified construction. The rest of the operation being the same as 25 hereinbefore described.

Though I have shown and described a particular construction, combination and arrangement, I do not wish to be limited to this particular construction, combination 30 and arrangement but desire to include in the purview of my invention the construction, combination and arrangement substantially as set forth in the appended claims.

Having thus described my invention what 35 I claim as new and desire to secure by Letters Patent, is:

1. In an ignition system, a current source comprising a magneto generator provided with permanent magnetic fields, an armature 40 with oppositely disposed poles, a commutator with oppositely disposed segments seventy degrees long, two brushes so positioned relatively to said commutator to collect current generated by the armature at 45 the highest peak of wave, condensers, the terminals of each connected to each brush of the magneto generator, a transformer with one terminal of the primary winding connected to one terminal of the condenser, 50 the other terminal of the condenser connected to a timer of the contact, a switch comprising a revoluble arm with a contact point on each oppositely disposed end adapted to engage with said contact twice in each revolution, 55 said switch connected to a terminal of the condenser, whereby two sparks are

produced with each revolution of said condenser.

2. In an ignition system, a current source comprising a magneto generator with permanent magnetic fields, a two-pole armature, a commutator with two segments oppositely disposed, two brushes so positioned in connection with said commutator to collect current generated by the armature at 60 the highest peak of wave, a pair of condensers connected in series, each condenser connected to a brush of the magneto generator, a conductor connecting said condensers, the primary winding of a transformer connecting with said conductor, the other side of said primary winding electrically connected to a double contact revoluble switch and a pair of contacts with which said switch engages, the terminal of one connecting with one of the brushes of said magneto generator and with one of said condensers and the terminal of the other contact connecting with the other switch of 70 said magneto generator and with the said 75 other condenser.

3. In an ignition system, a current source comprising a magneto generator with permanent magnetic fields, a two-pole armature, a commutator with two segments oppositely disposed, two brushes so positioned in connection with said commutator to collect current generated by the armature at 80 the highest peak of wave, a pair of condensers connected in series, each condenser connected to a brush of the magneto generator, a conductor connecting said condensers, the primary winding of a transformer connecting with said conductor, the other side of said primary winding electrically connected to a double contact revoluble switch and a pair of contacts with which said switch engages, the terminal of one connecting with one of the brushes of said magneto generator and with one of said condensers and the terminal of the other contact connecting with the other switch of 85 said magneto generator and with the said 90 other condenser.

In testimony whereof, I have hereunto set my hand at San Diego, California this 10th day of March 1916.

GUY H. SILVA.
